INVENTOR.

C. V. Salomon.

BY *Adam E. Fisher*

ATTORNEY.

UNITED STATES PATENT OFFICE.

CHESTER V. SALOMON, OF MILWAUKEE, WISCONSIN.

DESIGN FOR A UTENSIL-RACK.

● 54,685.

Specification for Design.

Patented Mar. 9, 1920.

Application filed April 14, 1919. Serial No. 290,100. Term of patent 7 years.

To all whom it may concern:

Be it known that I, CHESTER V. SALOMON, a citizen of the United States, residing at Milwaukee, in the county of Milwaukee, State of Wisconsin, have invented a new, original, and ornamental Design for Utensil-Racks, of which the following is a specification, reference being had to the accompanying drawing, forming a part hereof.

The figure is a perspective view of a utensil rack showing my new design.

I claim:

The ornamental design for a utensil rack as shown.

CHESTER V. SALOMON.

Witnesses:

A. W. SALOMON,
K. A. WALTERS.
